UNITED STATES PATENT OFFICE.

JOHN M. B. LEWIS, OF LYNCHBURG, VIRGINIA.

HEADLIGHT.

Application filed July 24, 1923. Serial No. 653,512.

To all whom it may concern:

Be it known that I, JOHN M. B. LEWIS, a citizen of the United States, residing at Lynchburg, in the county of Campbell and State of Virginia, have invented certain new and useful Improvements in Headlights, of which the following is a specification.

This invention relates to headlights and more particularly to headlights for automobiles, the arrangement of the various elements in the light being of a novel character whereby the usual glare in the eyes of approaching drivers is positively prevented.

It is an important object of the present invention to provide a headlight structure wherein the height of the uppermost ray of the light beam will at all times be below the legal height regardless of the adjustment of the light source.

20 A further object is the provision of means for adjusting the light source to secure proper focusing without bringing the machine upon which the lights are mounted, to a regular testing station.

25 Other objects and advantages of the invention will be apparent during the course of the following description.

In a copending application filed November 3, 1922, Serial No. 598,793, I have disclosed 30 a headlight construction wherein a light source is mounted within a reflector which is adapted to reflect rays of light upon a second reflector arranged in the upper part of the casing, the rays from the second reflector passing outwardly through the light opening in the forward part of the casing. I have found that the use of an elliptical reflector in place of the reflector shown in the above mention application permits of 35 more accurate control of the light rays while with the present construction a materially larger main reflector may be employed.

The present application is an improvement over the above mentioned application 45 and also my copending application Serial No. 652,442 filed July 18, 1923.

In the drawings, I have shown several 50 embodiments of the invention. In this showing,

55 Figure 1 is a central vertical longitudinal sectional view through a headlight embodying the present invention.

Figure 2 is a detail perspective of the 60 adjustable reflector and associated elements.

Figure 3 is a vertical longitudinal sec-

tional view through a modified form of reflector.

Figure 4 is a section taken on line 4—4 of Figure 3.

Figure 5 is a front elevation of the headlight.

Figure 6 is a section taken on line 6—6 of Figure 1, and,

Figure 7 is a fragmentary perspective of the smaller end of the elliptical reflector 65 and associated elements.

Referring to the drawings, the numeral 10 designates a casing as a whole, split as at 11 to provide upper and lower sections 12 and 13. The upper section 12 may be 70 provided with an outwardly off-set depending flange 14 surrounding the upper edge of the lower casing section as clearly shown. Suitable means is provided for supporting the casing upon the automobile. In the 75 drawings, I have shown a bracket 15 riveted as at 16 or otherwise secured beneath the casing and provided with a depending tubular member 17 to receive a support 18 as shown in Figure 5.

The forward end of the casing is provided with a light opening 19 in which is mounted preferably a plain glass 20 held in position by an apertured plate 21 as will be clearly understood.

An elliptical reflector 22 is mounted in the rear of the casing and is provided upon its smaller end with a tubular section 23 having a slot 24 therein as shown in Figure 7, for a purpose to be described. A bracket 25 is secured within the lower casing section by rivets 26 or the like and this bracket is provided with a portion 27 surrounding the tubular extension 23 but having its rear end 90 slightly spaced from the rear end of the tubular member 23. A sleeve 28 has its forward end mounted within the opening in the extension 23 and is provided upon one side with the usual bayonet slot (not shown) for the reception of a pin 29 carried by the base 30 of an electric light bulb 31. The sleeve 28 is provided with a spring contact 32 adapted to contact with the base contact of the light bulb as will be obvious. The sleeve 28 is provided with a pin 33 which is adapted to be received within the slot 24 of the tubular extension 23. The sleeve 28 is provided upon its outer surface and near its rear end with teeth 34 adapted to engage the threads of a screw 35 rotatably

mounted within the rear of the casing and adapted to be rotated by a suitable knob 36 as clearly shown in Figure 1.

Within the forward portion of the casing 5 and arranged slightly above the horizontal level of the upper limit of the light opening 19 is a substantially plane reflector 37. The reflector 37 is provided adjacent its longitudinal edges with ears 38 adapted to 10 rigidly receive a transverse shaft 39 journaled in opposite sides of the casing as at 40. One end of the shaft 39 extends beyond the casing and is provided with a depending portion 41 pivotally connected 15 with the forward end of an operating rod 42. The rear end of the rod 42 is adapted to be conveniently located near the seat of the driver in order that it may be readily operated. A coil spring 43 is mounted between 20 the rear end of the reflector 37 and the upper wall of the casing section 12 as shown in Figure 1. The spring 43 is of the compression type and is fairly heavy so as not to be affected by the jolts and 25 vibrations to which the automobile is subjected while traveling. A stop bracket 44 is secured to the upper wall of the casing section 12 above the forward end of the reflector 37. It will be obvious that the 30 spring 43 will urge the rear end of the reflector downwardly, movement of the latter being limited by the stop 44. The reflector 37 is so arranged within the casing that the center of its lower or reflecting 35 face will be arranged adjacent the focal point of rays of light from the elliptical reflector 22. It will be obvious that light rays cast by the reflector 22 will be reflected downwardly and outwardly by the reflector 40 37 through the light opening 19. Since the reflector 37 is arranged wholly above the level of the light opening 19 it will be obvious that it will be screened from the view 45 of drivers of vehicles approaching in the opposite direction.

A screen 45 is arranged within the lower casing section as shown in Figures 1 and 6 and this screen is arranged with its upper edge slightly spaced from the reflecting face 50 of the reflector 37. Inasmuch as the screen 45 is arranged almost directly beneath the focal point of the rays from the elliptical reflector it will be obvious that the upper 55 edge of the screen may be arranged in close proximity to the reflector 37 without interfering in any way with the light rays passing to or from this reflector. The screen 45 is adapted to be supported in position 60 by brackets 46 secured in any suitable manner within the lower casing section 13.

Means are provided for determining the proper focusing of the bulb 31 within the elliptical reflector 22. In the drawings, I 65 have shown a disk 47 pivotally mounted as at 48 upon one side of the screen 45, to

swing in a vertical plane. As is well known an elliptical reflector with a light source arranged at its principal focus will reflect light rays which converge substantially to a point at the conjugate focus of the reflector. I prefer to employ an elliptical reflector whose conjugate focus is in the same vertical plane as the rear face of the disk 47, for a purpose to be described. Obviously, the beam of light between the 70 screen 45 and the reflector 37 will be relatively narrow so that the upper edge of the screen may be arranged only slightly spaced from the reflector without interfering with the passage of the light beam.

The laws of some States not only limit the height of the uppermost rays of the light beams of automobile headlights but go even further in governing the distribution of light. In such cases it is required by statute that the rays of light cast from a headlight will form a resulting beam which will be substantially five feet in depth and extend not over four feet from the surface 85 of the road. It is similarly required that the light beams from the two headlights of an automobile must spread to a width of substantially twenty feet at a distance of seventy feet from the front of the vehicle. In Figures 3 and 4 of the drawings, I have 90 shown a somewhat modified form of reflector which may be substituted for the reflector 37 in the States having the more rigid regulations as to light distribution. As 95 shown, I provide a reflector 49 rigidly connected to the cross shaft 39 so as to be operated in the same manner as the reflector 37 previously described. When the reflector 49 is employed the lower or reflecting surface thereof is preferably arranged slightly below the focal point of the light rays from the reflector 22 in order that the beam cast upon this reflector will cover a substantial area. As shown in Figure 3, the reflecting 100 surface of the reflector 49 is convex longitudinally but is concave transversely as shown in Figure 4. When the reflector 49 is employed it will be seen that the upper rays 50 from the reflector 22 will be intercepted substantially to the rear of the reflector 49 in such a manner that the resulting ray 51 will pass downwardly at a slight angle through the glass 20. The lower rays 52 will be intercepted by the 105 forward portion of the reflector 49, the resulting rays 53 also passing outwardly through the glass 20. The rays 51 and 53 designating the lowermost and uppermost rays from the casing diverge only sufficiently to cast a beam of substantially five feet in depth as above described. The reflector 49 is formed with its reflecting surface concave transversely as previously described so that the rays reflected therefrom 110 will be confined within such an angle that 115 120 125 130

the resulting beam will be substantially twenty feet in width at a distance of seventy feet in front of the vehicle.

The operation of the device is as follows:

- 5 When a bulb is inserted within the reflector 22 the upper casing section is first removed. The light bulb is inserted in the usual manner and the knob 36 may be revolved to move the filament of the light 10 forwardly or rearwardly until the proper focus is reached. Rotation of the sleeve 28 is prevented by engagement of the pin 33 within the slot 24. The proper focusing 15 of the light may be determined by removing the upper casing section 12 and swinging the disk 47 to the dotted line position, shown in Figure 6, whereby a point on the rear face of the disk will coincide with the conjugate focal point of rays from the elliptical reflector. The bulb then may be moved 20 forwardly or rearwardly until the smallest possible spot of light is obtained on the disk 47. Thus it will be apparent that adjustment of the light and the determination 25 of the proper focus thereof may be had without resorting to any special testing apparatus. It will be obvious that when the device is in use the light source 31 and reflectors 22 and 37 will be wholly screened 30 from view from a point in front of the vehicle and above the upper limit of the light opening 19, when the vehicle is traveling upon a level street or road. When the vehicle is traveling up a hill and is approaching the top thereof, the driver of the vehicle, by moving the rod 42 rearwardly, may tilt the forward end of the reflector 35 downwardly to throw the rays of light on the road close to the vehicle in order that they may not be thrown into the eyes 40 of drivers of approaching vehicles.

It is to be understood that the form of my invention herewith shown and described is to be taken as a preferred example of the 45 same, and that various changes in the shape, size, and arrangement of parts may be resorted to without departing from the spirit of the invention or the scope of the subjoined claims.

50 Having described my invention, I claim:

1. A device of the character described comprising a casing having a light opening therein, an elliptical reflector mounted in said casing, said reflector and the conjugate 55 focus thereof being arranged on opposite sides of a horizontal plane passing through said light opening, a light source mounted in said reflector, and a second reflector arranged between said elliptical reflector and said light opening, said second named reflector being arranged with its reflecting surface near the focal point of light rays from

said elliptical reflector and wholly outside the vertical limits of said light opening.

2. A device constructed in accordance with 65 claim 1 having a screen arranged with its edge slightly spaced from the second named reflector and near the focal point of the light rays from the elliptical reflector.

3. A device of the character described 70 comprising a casing having a light opening therein, an elliptical reflector mounted in said casing, a light source mounted in said reflector, a movable reflector arranged between said elliptical reflector and said light opening, said second named reflector being arranged with its reflecting surface near the focal point of light rays from said elliptical reflector, and a focusing member mounted within said casing and movable to intersect 75 the axis of said elliptical reflector at its focusing point when said second named reflector is removed.

4. A device of the character described 85 comprising a casing having a light opening therein, an elliptical reflector mounted in said casing, a light source mounted in said reflector, a movable reflector arranged between said elliptical reflector and said light opening, said second named reflector being 90 arranged with its reflecting surface near the focal point of light rays from said elliptical reflector, a screen arranged with its edge slightly spaced from said second named reflector and near the focal point of light rays from said elliptical reflector, and a focusing member carried by said screen and movable to intersect the axis of said elliptical reflector at its focusing point when said second named reflector is removed. 100

5. A device of the character described comprising a casing having a light opening therein, an elliptical reflector mounted in said casing, a light source mounted in said reflector, means operable from without said casing for adjusting said light axially of said elliptical reflector, a second reflector arranged between said elliptical reflector and said light opening, and means adapted 105 to be arranged at the focusing point of light rays from said elliptical reflector for determining the proper focus of said light source.

6. A headlight including a casing, means for projecting a light beam which converges substantially to a focal point within said casing, an opaque member normally arranged wholly outside the path of travel of the light beam and adapted to be moved wholly across the normal path of the beam at its focal point to determine the proper focus of said light projecting means, and means for focusing said light projecting means. 115

In testimony whereof I affix my signature.
JOHN M. B. LEWIS.
